DESIGN FOR A COMBINATION HOISTING AND EXCAVATING MACHINE POWER UNIT

Hilbert E. Swanson, Milwaukee, Wis., assignor to
Universal Unit Machinery Corporation, West
Allis, Wis., a corporation of Delaware

Application September 16, 1944, Serial No. 115,325

Term of patent 14 years

(Cl. D14—3)

To all whom it may concern:

Be it known that I, Hilbert E. Swanson, a citizen of the United States, residing at Milwaukee, in the county of Milwaukee and State of Wisconsin, have invented a new, original, and ornamental Design for a Combination Hoisting and Excavating Machine Power Unit, of which the following is a specification, reference being had to the accompanying drawing, forming part thereof.

In the drawing,

Fig. 1 is a left-hand side elevational view of a combination hoisting and excavating machine power unit, showing my new design;

Fig. 2 is a right-hand side elevational view;
Fig. 3 is a front elevational view;
Fig. 4 is a rear elevational view, and
Fig. 5 is a top plan view.

The dominant features of the new design reside in the portions shown in full lines in the drawing.

I claim:

The ornamental design for a combination hoisting and excavating machine power unit, substantially as shown and described.

HILBERT E. SWANSON.
